DESIGN FOR A NEGLIGEE

Alice Macksoud, New York, N. Y.

Application January 20, 1948, Serial No. 143,895

Term of patent 3½ years

(Cl. D3—26)

To all whom it may concern:

Be it known that I, Alice Macksoud, a citizen of the United States of America, residing in New York City, county of New York, and State of New York, have invented a new, original, and ornamental Design for a Negligee, of which the following is a specification, reference being had to the accompanying drawing, forming part thereof, wherein,

I claim:

The ornamental design for a negligee, substantially as shown.

ALICE MACKSOUD.
